UNITED STATES PATENT OFFICE.

PETER F. GREENWOOD, OF CATASAUQUA, PENNSYLVANIA.

MANUFACTURE OF LINKS.

SPECIFICATION forming part of Letters Patent No. 310,415, dated January 6, 1885.

Application filed March 20, 1884. (No model.)

To all whom it may concern:

Be it known that I, PETER F. GREENWOOD, a citizen of the United States, residing in Cata-
sauqua, county of Lehigh, State of Penn-
sylvania, have invented a new and useful Im-
provement in the Manufacture of Links, which
improvement is fully set forth in the following
specification and accompanying drawings,
in which—

10 Figure 1 is a perspective view of a coil of
metal, illustrating the first operation of manu-
facturing links embodying my invention. Fig.
2 is a side view showing the subsequent form
of the metal. Fig. 3 is a section on line *x x*,
15 Fig. 2. Fig. 4 is a view of a link.

Similar letters of reference indicate corre-
sponding parts in the several figures.

My invention consists of a method of form-
ing a link from a bar of metal bent into a
20 spiral form, the coils being welded and dis-
tended in opposite directions, thus converting
the annular form of the coil into an ellipse,
whereby a strong, durable, and reliable arti-
cle is produced.

25 In carrying out my invention I take a bar
of flat iron of the desired length, shape, and
thickness and bend the same edgewise into
helical form, the coils of said helix being of
the same diameter and built up, as it were, one
30 on the other, substantially as shown in Fig. 1,
so that the coils are brought in contact and
not located one within the other, as is common.
The helix metal is now heated to a degree
necessary for welding, and placed on a cylin-
35 drical-shaped roll and subjected to suitable
rolls, which compress the coils one against the
other and thoroughly weld the same, forming
an annulus and round the exterior face of the
compressed coil, as shown in Fig. 2, the in-
40 terior face of the coil being flat, as shown in
Fig. 3.

It is evident that in lieu of rolls I may use
suitable dies, a press, or drop or steam ham-
mer to weld the coils and shape the same.
45 The annulus is now placed upon pins, (shown
in dotted lines, Fig. 3,) and motion commu-
nicated to said pins in opposite directions, the
effect of which is to elongate the annulus and

convert it into an elliptical or like shape, as
shown in Fig. 4.

50 It will be seen that I produce a strong, dura-
ble, reliable, and inexpensive link, and am
enabled to use inferior iron for the same, as
the fiber of the metal is continuous and coiled
in a manner so as to secure the greatest amount
55 of strength of which the metal is capable, and
there are no laps or butt-joints.

I am aware that it is not new to form a link
from a piece of metal the coils of which are
one within the other; but in this case, when
60 the coils are subjected to hammering or press-
ure, they are spread laterally, and thus opened
or imperfectly welded. In my case, as the
coils are of equal diameter or approximately
so, and placed one on the other, the rolling
65 thereon forces them one against the other in
the direction of the pressure, so that they are
reliably welded or united, and the fiber of the
metal is the same throughout the united coils,
owing to the uniform diameters of the latter.
70

Having thus described my invention, what I
claim as new, and desire to secure by Letters
Patent, is—

1. The improvement in the manufacture of
a link, consisting in coiling a bar of metal into
75 helical form, the coils being of equal diam-
eter and placed one on the other, rolling the
coils so as to weld the same, forming an an-
nulus, and then distending or elongating the
annulus, converting it into an ellipse or link
80 shape, substantially as and for the purpose
set forth.

2. A new and improved method in the manu-
facture of links for chains, consisting, first,
in coiling a flat bar of metal edgewise into a
85 helical form; second, rolling the coils so as to
weld the same and form an annulus having a
rounded outer face and a flat inner one; and,
third, in drawing out or elongating said an-
nulus until it is of an elliptical or link shape,
90 substantially as described.

PETER F. GREENWOOD.
